UNITED STATES PATENT OFFICE.

JAMES ATKISS, OF BROOKLYN, NEW YORK.

MACHINE FOR SLOTTING SOAP.

SPECIFICATION forming part of Letters Patent No. 252,711, dated January 24, 1882.

Application filed December 15, 1881. (No model.)

To all whom it may concern:

Be it known that I, JAMES ATKISS, a citizen of the United States, residing at Brooklyn, in the county of Kings and State of New York, 5 have invented new and useful Improvements in Machines for Slotting Soap, of which the following is a specification.

This invention consists in the combination of a soap-receptacle open at opposite ends and 10 constructed with a longitudinal partition dividing it into two compartments, a feed-hopper and delivery-spout common to both compartments of the soap-receptacle, the hopper being connected to the top and the delivery-spout to one end thereof, a knife pivoted to the delivery-spout to swing over the mouth thereof, two plungers working in the compartments of the soap-receptacle, respectively, and a double-crank shaft having its cranks connected to the 15 plungers to impart thereto alternate movements, so that when the receptacle is supplied with soap and motion is given to the crank-shaft the material is continuously forced out through the delivery-spout in shape of a bar, 20 which may be cut into desired lengths by means of the knife.

This invention is illustrated in the accompanying drawings, in which Figure 1 represents a vertical longitudinal section. Fig. 2 is 25 a horizontal section. Fig. 3 is an end view. Fig. 4 is a vertical cross-section.

Similar letters indicate corresponding parts.

The letter A designates the soap-receptacle, open at opposite ends, as shown, and constructed 30 with a longitudinal partition, B, whereby it is divided into two compartments, C D, the partition being located centrally, giving to the compartments like dimensions.

E denotes the feed-hopper, connected to the 35 top of the soap-receptacle, and F the delivery-spout, connected to one end thereof, the hopper extending the entire width of the receptacle and the spout converging from its inner sides or surfaces, so that the hopper and spout are 40 common to both compartments. The delivery-spout F is made detachable to allow the use of spouts having different shapes at their mouths, the shape thereof determining the cross-sec-

tion of the soap bar produced, the spout forming a die.

G indicates the knife, pivoted to the delivery-spout, as at H, this knife being arranged immediately next to the mouth of the spout, allowing it to be swung over or past the same, and being provided with a handle at its free 55 end.

I are the plungers, two in number, working in the compartments C D, respectively, and J the double-crank shaft, having its cranks K K' connected to the plungers, as by rods o. The 60 cranks K K' are arranged diametrically opposite to each other to impart alternate movements to the plungers I, and the cranks and plungers are so arranged relatively to the feed-hopper E that in the retrograde movement of 65 the plungers they are brought beyond the bottom or throat of the hopper, thus entirely exposing the same to the compartments of the soap-receptacle.

The soap is supplied to receptacle A through 70 the hopper E, and motion being imparted to the crank-shaft J, the plungers I act on the soap to force the same out through the delivery-spout F continuously and in shape of a bar, which may be cut or separated into desired lengths 75 by moving the knife G over the mouth of the spout.

What I claim as new, and desire to secure by Letters Patent, is—

The combination, substantially as hereinbefore set forth, of the soap receptacle, constructed with a longitudinal partition dividing it into two compartments, the feed-hopper and delivery-spout common to both compartments of the soap-receptacle, the swinging knife pivoted 80 to the delivery-spout, the plungers working in the compartments of the soap-receptacle, and the crank-shaft imparting to the plunger alternate movements, for the purpose specified.

In testimony whereof I have hereunto set my 90 hand and seal in the presence of two subscribing witnesses.

JAMES ATKISS. [L. S.]
